ILLINOIS, ASSIGNEES TO TROY LAUNDRY MACHINERY COMPANY, LTD., OF CHI-
CAGO, ILLINOIS, A CORPORATION OF NEW YORK.

SAFETY-GUARD FOR CENTRIFUGAL EXTRACTORS.

1,120,388.

Specification of Letters Patent.

Patented Dec. 8, 1914.

Application filed February 18, 1913. Serial No. 749,140.

To all whom it may concern:

Be it known that we, WILLIAM BARTHOLOMEW and JAMES F. BRODERICK, citizens of the United States, and FRITZ BALZER, a subject of the Emperor of Germany, residing at Chicago, in the county of Cook and State of Illinois, have invented certain new and useful Improvements in Safety-Guards for Centrifugal Extractors, of which the following is a specification.

Our invention relates in general to laundry machinery, and more particularly to centrifugal extractors.

The high speed at which the baskets of centrifugal extractors are rotated renders their use dangerous to careless operators unless such extractors are provided with safety appliances for preventing access to the baskets while they are rotating. In order that such safety devices may fully protect the operators, it is necessary that access should be prevented to the baskets not only while the power is applied to rotate them, but after the disconnection of the driving power and while the baskets continue to rotate by momentum at dangerous speeds.

The primary object of our invention is to provide a centrifugal extractor in which the cover must be locked in closed position when power is applied to rotate the basket, and in which the cover cannot be unlocked while the basket continues to rotate.

A further object of our invention is to provide a centrifugal extractor having a cover for preventing access to the revolving basket, in which power can only be applied to the basket after the cover has been locked, and in which the driving means which necessarily rotates while the basket rotates will be so connected with the cover that it cannot be opened until such driving means have ceased to move.

A further object of our invention is to provide an improved centrifugal extractor, which will be simple in construction and operation, and the use of which will be unattended by any possible injury to the operators.

Our invention will be more fully disclosed hereinafter with reference to the accompanying drawings, in which the same is

illustrated as embodied in a convenient and practical form, and in which—

Figure 1 is an elevational view; Fig. 2, an enlarged detail plan view; Fig. 3, an enlarged detail elevational view of the cover lock; Fig. 4, an enlarged detail elevational view of the lock, looking from the right in Fig. 3; Fig. 5, a detail elevational view on line 5—5, Fig. 1, of one of the idler guide pulleys of the driving belt; and Fig. 6, a detail plan view of the idler pulley and adjacent parts actuated thereby.

The same reference characters are used to designate the same parts in the several figures of the drawings.

Reference letter A indicates the casing of a centrifugal extractor in which is inclosed the usual revolving basket a.

B designates a suitable support for the casing A comprising standards and a base b adapted to be supported upon the floor.

C designates a cover for closing the top of the casing, thereby preventing access to the inclosed basket.

D designates a vertical spindle upon the upper end of which the basket is supported and to which power is applied for rotating the same and thereby imparting revolution to the basket.

d designates a pulley secured concentrically around the spindle D which is engaged by a driving belt E.

F designates one of a pair of idler pulleys around which the belt E passes and by which it is guided to the pulley d. Any suitable means (not shown) may be provided for applying power to, and disconnect power from, the belt E when it is desired to impart rotary motion to the basket or to discontinue the rotation of the basket.

G designates a bracket suitably mounted upon the base b, as by means of lugs g overlying and secured to the base b of the standard B. The bracket G supports the pair of idler pulleys, one of which is designated F. Any suitable means may be provided for suitably journaling the idler pulleys upon the bracket G.

Secured to the guide pulley F are a series of lateral studs H which may be conveniently fastened to the spokes of the pulley.

K designates a lever fulcrumed at L upon the outer end of the bracket G, and having a path of movement which will project one end thereof into the path of rotation of the studs H. The opposite end of the lever K is provided with a weight k which normally oscillates the lever K to a position out of the path of the studs H, as shown in Fig. 5. A rod M is pivotally connected to the lever K intermediate of its fulcrum L and the pulley F. The upper end of the rod M is pivotally connected to the short arm of a bell crank lever N, the latter being fulcrumed at n upon the rear outer surface 15 of the water-guard a'.

O designates a bolt pivotally connected to the bell crank lever N by means of a slot and pin connection, as shown in Fig. 3. The bolt O extends through and is guided by a 20 pair of spaced lugs O' and O² secured to the water-ring a' in any suitable manner, as by means of bolts and nuts o' o².

P designates a link pivotally connected at one end to a bracket p upon the rear 25 edge of the cover C. The opposite end of the link P extends through an opening in the water-guard a' intermediate of the spaced ears O' and O², and is pivotally connected to the upper end of a link R. The link R is suitably pivoted at its lower end 30 upon the bracket S also secured to the water ring a'. The bracket S is shown as comprising a pair of spaced ears s which rotatively support a pin s' which is surrounded by a sleeve r interposed between the spaced ears s and with which the link R is integrally 35 formed.

The operation of our invention is as follows: When the cover is in its open position, as indicated in dotted lines in Fig. 4, the link P is reciprocated toward the rear by reason of the eccentric position of the bracket p with relation to the hinges c which pivotally connect the cover with the water-ring A' around the top of the casing A. The position of the link P when the cover is raised moves the opening p' in the link beyond the path of movement of the bolt O so that the bolt O when the cover is 40 opened cannot be reciprocated toward the left in Fig. 3, as the end of the bolt engages the imperforate portion of the link between the guide ears O', O² of the bolt. The bolt is thereby retained in the position shown 45 in dotted lines in Fig. 3, and in such position the rod M is depressed and the detent lever K swung into such position that the end thereof is in the path of the studs H on the spokes of the pulley F. The extractor, 50 therefore, cannot be operated, inasmuch as one of the studs H would engage the end of the detent lever K and thereby prevent the turning of the pulley and consequently prevent the movement of the belt relatively 55 to the pulley on the basket spindle D. When

it is desired to rotate the basket after placing therein the articles to be treated, the cover C is closed, which moves the link P forwardly through the slot in the water-guard a' until the opening p' in the link 70 registers with the path of movement of the bolt O. The bolt O is then moved toward the left in Fig. 3 by applying pressure to the upper end of the bell crank lever N. This movement of the bolt causes the same to 75 pass through the hole p' and the link P thereby locking the cover closed. Such movement of the bolt O lifts the rod M, thereby oscillating the detent lever K so that the end thereof will be moved out of 80 the path of the studs H. The power may then be applied to the bolt O as the idler pulley F may freely rotate without the studs thereon engaging the end of the detent lever. If, during the driving of the basket, 85 an effort should be made to unlock the cover by reciprocating the bolt O toward the right in Fig. 3 to disengage it from the link P, such movement of the bolt will be prevented by the rapid engagement of the studs H 90 with the end of the detent lever K. The detent lever therefore cannot be moved in the direction necessary in order to permit the bolt to be disengaged from the link, thereby positively preventing the unlocking 95 of the cover as long as the basket continues to revolve, inasmuch as the idler F must revolve coincidentally with the revolution of the basket owing to the engagement 100 of the driving belt E with the idler pulley F and also with the pulley d on the basket spindle D.

The weight k on the detent lever K normally oscillates such lever so as to lift the rod M and thereby oscillate the bell crank 105 lever N so as to reciprocate the bolt O through the hole p' in the link P. Consequently, immediately upon the closing of the cover the bolt will automatically lock 110 the same closed. The movement of the bell crank lever toward the right in withdrawing the bolt from engagement with the link is limited to the stop pin T secured to the rear surface of the water-guard a'.

From the foregoing description it will be 115 observed that we have invented improved safety mechanism for centrifugal extractors, and similar machines, by means of which the cover can only be opened by shifting the locking bolt, and that the locking 120 bolt cannot be so shifted while the basket revolves. It will be further observed that in our improvement the basket can not be driven until the cover has first been closed.

Our invention more specifically involves 125 unlocking mechanism between the cover and one of the rotating members of the power driving mechanism, so that the power driving mechanism cannot operate when the cover is open and the cover cannot be opened 130

while the power driving mechanism, and with it the basket, continues in operation.

While we have illustrated and described our invention as embodied in a centrifugal extractor and have defined the same in the following claims with reference to such embodiment thereof, yet we do not wish thereby to be understood as restricting the application of our invention to centrifugal extractors, but intend thereby to protect it for whatever uses it may be adapted and in whatever forms it may be capable of practical embodiment.

What we claim is:

15. 1. In a centrifugal extractor, the combination with a basket, of driving means for rotating said basket, a cover for closing said basket, and mechanism controlling the opening and closing of said cover comprising a movable detent extending into the path of spaced rotating parts of the driving means when the cover is open, said detent being retained in position to prevent the cover being opened by the impact of said rotating parts of the driving means.
20. 2. In a centrifugal extractor, the combination with a basket, of driving means for rotating said basket, a cover for closing said basket, a bolt for locking said cover closed, and means controlled by said driving means for preventing the disengagement of said bolt from the cover during the rotation of the basket.
25. 3. In a centrifugal extractor, the combination with a rotary basket, of a casing within which said basket is inclosed, a cover pivotally mounted on the casing, means for rotating said basket, a bolt supported upon said casing, a keeper connected with said cover and moved thereby into position to be engaged by said bolt only when the cover is closed, and means connected with said bolt for preventing the operation of the driving means when the bolt is disengaged from said keeper.
30. 4. In a centrifugal extractor, the combination with a rotary basket, of a casing within which said basket is inclosed, a cover pivotally mounted on the casing, means for rotating said basket, a bolt pivotally supported upon said casing, a keeper connected with said cover and moved thereby into position to be engaged by said bolt only when the cover is closed, and means controlled by said driving means for preventing the disengagement of said bolt from said keeper during the operation of the driving means.
35. 5. In a centrifugal extractor, the combination with a rotary basket, of a casing in which said basket is inclosed, a cover pivotally mounted on said casing, means for rotating said basket, a bolt mounted upon said casing, a link connected with and reciprocated by said cover in a path intersecting the path of said bolt, said link when said
40. cover is closed being in position to be engaged by said bolt and when said cover is open forming an obstruction to the movement of said bolt, and means connected with said bolt for permitting the operation of said driving means only when said bolt is in engagement with said link.
45. 6. In a centrifugal extractor, the combination with a rotary basket, of a cover for closing said basket, means for rotating said basket, a bolt for locking said cover closed, a bell crank lever operatively connected with said bolt, a movable detent connected with said bell crank lever and extending into the path of spaced rotating parts of the means for rotating the basket when the cover is open, said detent being retained by the impact of said rotating parts in position to actuate said bell crank lever to prevent the unlocking of said bolt.
50. 7. In a centrifugal extractor, the combination with a rotary basket, of a casing inclosing said basket, a cover pivotally mounted on said casing, a bolt for locking said cover closed, driving means for rotating said basket, a bell crank lever pivotally mounted upon said casing and operatively connected with said bolt, a reciprocating rod connected with said bell crank lever, a movable detent operatively connected with said rod and extending into the path of spaced rotating parts of the driving means when the cover is open, said detent being retained by the impact of said rotating parts in position to cause said rod and bell crank lever to retain said bolt in locked position.
55. 8. In a centrifugal extractor, the combination with a rotary basket, of a casing inclosing said basket, a cover pivotally mounted on said casing, a bolt for locking said cover closed, driving means for rotating said basket, a bell crank lever pivotally mounted upon said casing and operatively connected with said bolt, a reciprocating rod connected with said bell crank lever, a detent lever pivotally connected with said rod, and a projection on a member of said driving means having a path intersecting the path of said detent lever, thereby preventing the movement of said detent lever necessary to permit said cover to be unlocked.
60. 9. In a centrifugal extractor, the combination with a rotary basket, of a cover for said basket, driving means for rotating said basket comprising a belt and a pulley engaged by the belt, a projection on said pulley, locking means for retaining the cover closed, and a detent operatively connected with said locking means and extending into the path of said projection when the cover is unlocked.
65. 10. In a centrifugal extractor, the combination with a rotary basket, of a cover for said basket, driving means for rotat-

ing said basket comprising a belt and an idler pulley engaged by said belt, studs fixed to and projecting laterally from the spokes of said idler pulley, locking means for retaining said cover closed, and a detent operatively connected with said locking means and extending into the path of said studs when the cover is unlocked.

11. In a centrifugal extractor, the combination with a casing, of a rotary basket within said casing, a cover for said casing, a bolt mounted upon said casing for locking said cover closed, a bell crank lever pivotally mounted upon said casing and operatively connected with said bolt, a reciprocating rod connected with said bell crank lever, driving means for rotating said basket comprising a belt, and an idler pulley engaged by the belt, studs projecting laterally from the spokes of said pulley, and a detent lever pivotally connected with said rod and extending into the path of said studs when said bolt is in unlocked position relatively to said cover.

12. In a centrifugal extractor, the combination with a casing, of a rotary basket within said casing, a cover for said casing, a link connected with and reciprocated by said cover, a bolt mounted upon said casing and having a path intersecting the path of said link, said link when said cover is closed being in a position to be engaged by said bolt, and when said cover is open forming an obstruction to the movement of said bolt, a bell crank lever pivotally mounted upon said casing and operatively connected with said bolt, a reciprocating rod connected with said bell crank lever, driving means for rotating said basket comprising a belt and a pulley engaged by the belt, studs carried by said pulley, and a detent lever piv-

totally connected with said rod and extending into the path of said studs when said bolt is disengaged from said link.

13. In a centrifugal extractor, the combination with a rotary basket, of a cover for said basket, driving means for rotating said basket comprising a belt and a pulley engaged by the belt, and means for preventing the opening of said cover during the rotation of the basket comprising a movable detent extending into the path of rigid rotary portions of said pulley when the cover is open, said detent being retained in position by the impact of the said rigid portions of the pulley to prevent the cover being opened during the rotation of the basket.

14. In a centrifugal extractor, the combination with a rotary basket, of a cover for said basket, a vertical spindle upon which said basket is supported, a pulley fixed to said spindle, a driving belt engaging said pulley to rotate said spindle and basket, a pair of guide pulleys supported upon the extractor base around which the driving belt passes to and from the spindle pulley, a movable detent supported adjacent one of said guide pulleys and adapted to project into the path of rotation of fixed portion of said guide pulley, a rod operatively connected to said detent at its lower end, and means connected to the upper end of said rod to control the opening and closing of said cover.
